UNITED STATES PATENT OFFICE.

OTTO A. HOKANSON, OF WOODSTOCK, ILLINOIS, ASSIGNOR TO WOODSTOCK TYPE-
WRITER COMPANY, OF WOODSTOCK, ILLINOIS, A CORPORATION OF ILLINOIS.

PLATEN-CARRIAGE SHIFT AND REBOUND LOCK FOR TYPEWRITERS.

Application filed January 31, 1924. Serial No. 689,612.

This invention relates to the case shift mechanism for typewriters and has for its object the provision of such mechanism which shall be of improved construction and operation, and in which the platen carriage will be locked against rebound movement during case shift, and in which the carriage may be locked in its upper position and released from either side of the keyboard.

10 The invention is exemplified in the combination and arrangement of parts shown in the accompanying drawing and described in the following specification, and it is more particularly pointed out in the appended claims.

In the drawing—

Fig. 1 is a side elevation of a typewriter, with parts broken away and in section, showing one embodiment of the present invention; and

Fig. 2 is a fragmentary view showing the shift lock at the right-hand side of the keyboard.

The invention is illustrated in the drawing as applied to the construction of a "Woodstock" typewriter, but it will be understood that it is applicable to various machines having case shift mechanism.

In the drawing, the numeral 10 designates the frame-work of a typewriter having a platen carriage 11 mounted to travel on ways 12. The platen carriage 11 supports a shiftable platen frame 13 carried by links 14. The frame 13 carries a transverse rod 15 to which is secured a downwardly extending bracket 16. At the lower end of the bracket 16 a roller 17 is journaled which travels on a shift rail 18. A retainer 19 is secured to the bracket 16 and the lower end is hooked about the shift rail 18 to prevent upward movement of the platen away from the rail. The shift rail 18 is carried by a shift frame 20 which is pivoted at 21 on the main frame of the machine.

45 A pair of shift levers 22 and 23, one at each side of the typewriter, have upwardly extending arms 24 for engagement with the shift frame 20 to lift the platen carriage for case shift when the shift keys are depressed.

50 The key levers 22 and 23 are pivotally supported at 25 on the frame of the machine and are provided with springs 26 to hold them in their upper position. Each key lever 22 is provided with a locking key 27

55 pivoted at 28 to the key lever and having a

catch shoulder 29 for engaging a fixed catch 30 secured to the side of the main frame.

A coil spring 31 normally holds the lock key in retracted position so that when the key lever 22 is depressed by operating the fixed key 32 thereon the shift lock will not engage the catch 30 and the platen will return to its lower position as soon as the key 32 is released. If the key 32 is depressed, however, the lock shoulder 29 will be moved into engagement with the catch 30 at the same time that the lever 22 is moved downwardly so that the lever will be locked in its lower position and the platen will be retained in its uppermost position.

70 The shift lever may be released by pressing the key 32 which will relieve the pressure on the shoulder 29 and permit the spring 31 to withdraw the shoulder from engagement with the catch 30. When the shift key is locked in its lowermost position it is desirable to be able to release it from either side of the keyboard and for this purpose a shaft 34 is journaled in the frame of the machine and extends entirely across the machine from one side to the other. A pair of dogs 35 and 36 are attached to the shaft 34, one at each side of the machine, the dogs having contact shoulders 37 which are in position to engage the lower ends of the locking levers 27 when the levers are in engagement with the catches 30. The dogs 35 and 36 are extended upwardly past the shaft 34 and are adjustably connected by screws 38 to cam levers 39. The levers 39 have cam faces 40 disposed adjacent pins 41 secured to the levers 22 and 23, respectively.

75 It will be apparent that each time either of the levers 22 or 23 is depressed one or the other of the cam levers 39 will be operated to oscillate the shaft 34 so that if either of the shift locks 27 is in engagement with its catch 30 the abutment 37 will engage the lower end of the locking lever and force it out of contact with its catch, thus 80 releasing the shift key. In this manner either shift lock may be released by depressing the shift key at either side of the keyboard. A coil spring 42 normally holds the cam lever 39 at its limit of movement 85 toward the pin 41.

90 The weight of the platen and supporting frame is partially counterbalanced by coil springs 43 secured to the shift frame 20 and in the absence of some device for locking the 95

platen carriage in its lowermost position there is a tendency of the carriage to rebound when the shift key is released and the carriage drops to its downward limit of movement as determined by the stops 44. To overcome this tendency an arm 45 is mounted on the pivot 21 which carries the shift frame 20 and is adjustably connected to the shift frame by a screw and slot connection 46. A lever 47 is mounted at the left-hand side of the machine on the pivotal support 48 for the sub-levers and is provided with a contact face 49 for engaging a pin 50 on the lower end of the arm 45. A depression 51 is provided at the rear end of the contact face 49 for receiving the pin 50. When the pin 50 is seated in the depression 51 the shift frame 20 is locked against movement. The link 52 connects the lever 47 with an extension 53 on the dog 35 at the left-hand side of the machine frame. The link 52 and extension 53 are connected by a pivot pin 54 which engages an elongated slot 55 in the link 52.

25 A slight amount of lost motion is provided at 56 between the arm 24 of the shift lever 22 and the contact abutment for the shift frame 20. When a shift key is depressed the pin 41 will impart a slight movement to the cam 39 and consequently to the extension 53 before the arm 24 comes in contact with the shift frame 20. This preliminary movement will rotate the lever 47 in a clockwise direction a sufficient amount 30 to free the pin 50 from the depression 51 and permit movement of the shift frame when the arm 24 engages the shift frame.

During the shifting movement of the platen the pin 50 will travel along the contact face 49, thus holding the lever 47 in its depressed position. When the shift key is released the arm 45 will move backwardly along the contact face 49 until the pin 50 registers with the depression 51 at which 40 time the coil spring 57 will draw the link 52 forwardly and snap the lever 47 upwardly to cause the depression 51 to engage the pin 50 and thus lock the platen carriage against rebound movement. It will thus be seen 45 that the mechanism provides a lock for the carriage when it reaches its lower position and prevents any rebound which might result in blurring of the letters. Means is also provided for locking the platen in its upper position by a key at either side of the keyboard and the carriage may be released by pressing the shift key at either side of the keyboard irrespective of the side at which the shift lock key has been operated.

I claim:

1. The combination with a shiftable element for changing from one case to another, of a key lever for shifting said element, a locking lever for retaining said element

against movement, a pivoted arm, a link connecting said locking lever and arm and having a pin and slot connection with said arm, a cam connected with said arm, and a contact member on said case shift lever for 70 moving said arm.

2. In a typewriter, a main frame, a platen carriage mounted to travel on said frame, a vertically shiftable platen on said platen carriage, a shift frame mounted on said main frame, a shift rail carried by said shift frame, a roller connected with said platen for traveling on said shift rail, a detent connected with said platen for holding said roller against movement away from said rail, a counterbalance spring connected with said shift frame, an arm adjustably connected with said shift frame and having a pin thereon, a locking lever having an elongated contact face for engaging said pin and having a depression at one end of said face for locking said pin to hold said shift frame against upward movement, a pair of case shift key levers, a shaft extending transversely of said frame and having an arm 90 secured thereto, a link pivotally connected with said locking lever and having a pin and slot connection with said arm, a pair of cam levers adjustably mounted on said transverse shaft, and means on each of said case shift key levers for engaging one of said cam levers to rock said shaft and release said locking lever from said pin at the beginning of a case shift movement.

3. In a typewriter, a pair of case shift levers each having a shift key thereon, a shift lock connected with each of said levers and having a locking key thereon, a transverse shaft, means on said shaft for releasing said shift locks, and means for actuating said shaft when either of said shift keys is operated.

4. In a typewriter, a pair of separately movable case shift levers, independently operating shift locks mounted one on each of said levers, means for releasing the shift locks on either of said levers when the lever upon which said shift lock is mounted is depressed, and means operated upon depression of either of said levers for releasing the 115 shift lock on the other of said levers.

5. In combination, a pair of shift levers each having a shift lock mounted thereon provided with a lock key, a spring for retaining said shift lock in retracted position, a transverse shaft having a pair of contact devices thereon for engaging said shift locks to release the same, and a pair of cam members on said shaft arranged to cooperate with said shift levers to rotate said shaft 120 upon operation of either of said shift levers.

6. The combination with a shiftable element for changing from one case to another, of a lock for preventing rebound of said element, a shaft for releasing said locks, a pair 130

of case shift levers, shift locks connected one with each of said levers, detents engaged by said locks, means on said shaft for releasing said shift locks, and means for operating said shaft when either of said case shift levers is depressed.

7. The combination with a vertically shiftable platen, of a lock for preventing rebound of said platen, a pair of case shift levers, shift locks for said levers, detents

for said shift locks, a common device operated by either of said case shift levers when depressed, means operated by said device for releasing said rebound lock, and means operated by said device for releasing either of said case shift locks.

15

In testimony whereof I have signed my name to this specification on this 29th day of January, A. D. 1924.

OTTO A. HOKANSON.
